INVENTOR

Albert Henderson
by his Atty
Bynes, Stetton & Pannell

UNITED STATES PATENT OFFICE

ALBERT HENDERSON, OF PITTSBURGH, PENNSYLVANIA, ASSIGNOR TO HENDERSON & HATCHER, INC., OF PITTSBURGH, PENNSYLVANIA, A CORPORATION OF DELAWARE

STEP

Application filed October 12, 1928. Serial No. 312,144.

This invention relates to steps and is particularly useful for the manufacture of step units from cementitious material. It provides a precast step member which may be used in concrete construction for porch steps and the like. The step member is flexible in that it may be used for steps having varying ratios of tread width and riser height. It is light in weight, strong, and economical 10 to manufacture.

I provide a tread having an integral riser, the tread having end portions extending beyond the riser and forming the supports for the step member. In making up a set of 15 steps end walls are first built up and the step members are laid thereon. The endwise projecting portions of the treads lie over the end walls and the risers are of such width as to fill the space therebetween. Each riser 20 lies behind the tread of the next lower step, and may extend beneath the same in an amount depending on the riser height. Since the depending portion of the riser is concealed within the structure this does not detract from the appearance. It materially 25 simplifies the construction, as a single step unit of standard width will take care of any stairway, regardless of the variations in riser height.

Reinforcing means is preferably employed, this reinforcing extending from the projecting end portions of the tread into the riser.

In the accompanying drawings, illustrating 35 the present preferred embodiment of the invention,

Figure 1 is a front elevation of a step structure embodying the invention,

Figure 2 is an end elevation thereof,

Figure 3 is a section taken on the line 40 III—III of Figure 1,

Figure 4 is a front elevation of one of the step members,

Figure 5 is an end view thereof,

Figure 6 is a perspective view of the step 45 member, and

Figure 7 is a top plan view of one of the blocks employed for making the end walls.

Figures 1, 2 and 3 show a set of cement 50 steps adjacent a building indicated generally by the letter B. The steps consist of spaced

end walls built up of cement blocks 2 and special precast step members. Each step member comprises a tread 3 and a riser 4. The treads extend beyond the risers, as indicated at 5, and overlie the blocks 2. The 55 risers 4 are of such width that they just fill the space between the end walls, as is shown in Figure 1.

It will be noted from Figure 3 that each riser 4 lies behind the rear face 6 of the tread 3 for the next lower step in the structure. If it is desired to make a stairway of a different pitch, blocks 2 of different height are selected, and while in such structure the rear face 6 abuts the adjacent riser 4 the bottom face 7 of the riser may lie in a different vertical position relative to the adjacent tread.

Reinforcing rods 8 are provided, one of which extends downwardly into the riser 4. 70 All of the reinforcing rods extend into the end portions 5 so as to adequately strengthen the step structure.

When the structure is set up the step members are properly grouted in so that a unitary 75 waterproof set of steps is produced.

While I have illustrated and described the preferred embodiment of my invention, it is not limited to this form but may be otherwise embodied within the scope of the following claims.

I claim:

1. A cementitious step member, comprising a tread, an integral riser, the tread extending beyond the riser, whereby a supporting surface is provided under the ends of the tread and reinforcing extending from the riser into the extended portion of the tread.

2. A step structure, comprising spaced supports, and a cementitious step member associated therewith the step member having a tread and an integral riser, the riser lying exclusively between the supports and the tread extending over the upper surface of the supports, whereby the entire step member is supported by the tread.

3. A precast step structure, comprising a plurality of cementitious treads having integral risers, a riser for one tread extending down below the next lower tread in the struc-

ture, said lower tread slidably abutting the face of the riser whereby steps of varying riser heights may be constructed without affecting the appearance of the front of the step structure.

- 5 4. A step structure, comprising spaced supports, and a plurality of cementitious treads carried thereby, the treads having integral risers of a length substantially equal to the distance between the supports, the treads proper extending over the supports, a riser for one tread lying behind the next lower tread in the structure, said lower tread abutting the face of the riser.
- 10 5. A step member, comprising a tread having an integral riser, the tread extending beyond the riser, the extended portion being adapted for exclusively supporting the step member.
- 15 6. A step structure, comprising spaced supports, each of said supports including a plurality of blocks of predetermined size associated with each other in fixed relationship to form a plurality of co-acting treads and risers, and a plurality of cementitious step members associated with said spaced supports, each of said step members having a tread and an integral riser, the riser lying exclusively between the supports and having its front face in substantially the plane of the corresponding front faces of the risers of the spaced supports and the tread of the step extending over the corresponding steps of the spaced supports, said supports supporting said steps at the areas of contact between the extended step treads and the support steps, the size of said steps having a predetermined dimensional relation with the size of said support blocks, the relative vertical position of said steps depending upon the riser height of the supports and being adjustable without affecting the front appearance of the step structure.
- 20 35
- 25 40

In testimony whereof I have hereunto set my hand.

ALBERT HENDERSON.
